DESIGN FOR A CLOCK

Thomas D. Di Addario, Buffalo, N. Y.

Application March 2, 1948, Serial No. 144,861

Term of patent 14 years

(Cl. D42—7)

To all whom it may concern:

Be it known that I, Thomas D. Di Addario, a citizen of the United States, residing at Buffalo, in the county of Erie, State of New York, have invented a new, original, and ornamental Design for a Clock, of which the following is a specification, reference being had to the accompanying drawing, forming part thereof.

Figure 1 is a top plan view of a clock embodying my new design.

Figure 2 is an elevation thereof.

I claim:

The ornamental design for a clock, as shown.
